UNITED STATES PATENT OFFICE

JULIUS FRICK, OF MILWAUKEE, WISCONSIN

STAIR STRUCTURE

Application filed January 21, 1932. Serial No. 587,947.

This invention relates in general to improvements in the art of constructing stairways, and relates more specifically to improvements in stair structures formed of concrete or the like.

An object of the invention is to provide an improved stair structure which may be constructed of concrete or other moldable plastic material.

Another object of the invention is to provide a sectional stairway construction composed of individual tread elements which may be readily manufactured and assembled.

A further object of the invention is to provide improved stairs which are strong, fire-proof, and leakproof in construction, and which present a neat and highly finished appearance.

Still another object of the invention is to provide a reinforced stair tread structure especially adapted for use in assembling compact stairways in large office buildings or the like.

Another object of the invention is to provide an improved stairway structure of the type wherein one side may be interlocked with a wall while the other side may be left open.

A further object of the invention is to provide improved structure for rigidly connecting the ends of stairs or stair sections to the adjacent floors or platforms.

Still another object of the invention is to provide an improved end tread for sectional stairs, which is especially applicable to the adjoining upper and lower ends of reversely directed stairways extending upwardly and downwardly from a common platform or floor.

Another object of the invention is to provide various other improvements in the details of construction and in the mode of manufacturing sectional stairways, whereby a durable and attractive assembly may be produced at minimum cost.

These and other objects and advantages will be apparent from the following detailed description.

A clear conception of an embodiment of the several features of the invention, and of the method of constructing and of assem-

bling sectional stairs built in accordance with the improvement, may be had by referring to the drawings accompanying and forming a part of this specification in which like reference characters designate the same or similar parts in the various views:

Fig. 1 is a top view of a pair of adjacent oppositely directed stairway portions extending upwardly and downwardly from a common platform;

Fig. 2 is a side elevation of the stair assembly shown in Fig. 1, the forward supporting wall having been omitted;

Fig. 3 is a top view of the special tread used at the adjacent ends of oppositely directed stair sections, and of one of the end blocks;

Fig. 4 is a front view of the special tread and end block of Fig. 3;

Fig. 5 is a transverse vertical section through the special tread, taken on the line 5—5 of Fig. 4;

Fig. 6 is a transverse vertical section through the special tread, taken on the line 6—6 of Fig. 4;

Fig. 7 is a part sectional top view of one of the intermediate standard treads, and of one of the end finish blocks;

Fig. 8 is a front view of the standard tread and block of Fig. 7;

Fig. 9 is a transverse vertical section through the standard tread, taken on the line 9—9 of Fig. 8; and

Fig. 10 is an end view of the standard tread and end block.

While the invention has been shown and described herein as being specifically applied to a sectional stairway wherein one end of each section is embedded in an adjacent wall, it should be understood that some of the features are more generally applicable to stairs either of the type wherein both ends of the treads are embedded in walls, or of the type wherein both sides of the stairway are open and devoid of confining walls.

Referring to the drawings, the improved stairway specifically shown, comprises in general a series of similar individual treads 12, a special end tread 13 coacting with the lowermost of the individual treads 12, a special end tread 14 coacting with the upper-

most of the individual treads 12, and a special double-length intermediate tread 15 coacting with the upper and lower treads 12 of the adjacent stair groups or sections. End finish blocks 16 coat with the end portions of the treads and are embedded with the tread ends, in concrete walls 17 as shown in Fig. 1, so that a desirable base ledge is formed by the exposed ends of the blocks 16. The treads 12, 13, 14, 15 and the blocks 16 are preferably formed of concrete or other moldable material having fire and water-proof characteristics.

The individual treads 12 are preferably of identical construction, and each of these treads has a tongue 18 extending along one edge and a correspondingly shaped groove or recess 19 extending along the opposite edge thereof, as shown in Figs. 2, 7, 8, 9 and 10. The tongue 18 of one tread 12 is thus capable of coacting snugly with the groove 19 of an adjoining tread, and if the treads are to be used in open stairways, the tongues 18 and grooves 19 are preferably formed of less length than the treads 12 so that they will not be visible at the exposed ends of the treads when assembled. Each of the treads 12 may be provided with one or more longitudinal reinforcing elements or bars 20 and with one or more transverse through openings or holes 21. During assembly of the treads 12, they are strung in succession upon inclined assembly rods 22 which pass through the holes 21 and are provided with end clamping nuts 23 for forcing and retaining the adjacent treads in intimate contact with each other.

The lower end tread 13 is provided with a groove 19 at one edge, adapted to receive the tongue 18 of the lowermost tread 12, and has a groove 24 along its opposite edge adapted to interlock with the concrete of the lower floor 25. The tread 13 is also reinforced by one or more bars 20, and the lower end of the stringer rod 22 is embedded in the tread 13.

The upper end tread 14 is provided with a tongue 18 at one edge, adapted to coact with the groove 19 of the uppermost tread 12, and has a groove 24 along its opposite edge adapted to interlock with the concrete of an upper floor 26. The tread 14 is likewise reinforced by means of one or more bars 20, and the upper end of the stringer rod 22 and the clamping nut 23 coacting therewith, are normally embedded in the concrete of the floor 26.

The intermediate tread 15 is shown in detail in Figs. 3, 4, 5 and 6, and substantially comprises a set of special treads 13, 14 formed integral with each other and disposed end to end and with their tread surfaces 27 lying in the same plane. The tread 15 has a tongue 18 extending along substantially one-half of one edge, adapted to interlock with the edge groove of the upper tread 12 of the lower

stair section; and also has a groove 19 extending along substantially the other half of the same edge, adapted to interlock with the edge tongue of the lower tread 12 of the upper stair section. The entire opposite edge of the intermediate tread 15 is provided with a groove 24 adapted to interlock with the concrete of a platform 28. The tread 15 may likewise be reinforced by bars 20, and the stringer rods 22 of the upper and lower stair sections coact with the intermediate tread 15 as clearly shown in Figs. 1 and 2.

The end finish blocks 16 are formed as shown in Figs. 3 to 10 inclusive, and are normally embedded in the concrete of the walls 17 as indicated in Fig. 1, so that only about one inch of the blocks protrudes beyond the wall surface. This projecting portion of the blocks may subsequently be dressed to provide a neat appearing base. Posts 29 may also be provided adjacent to the special treads 13, 14, 15 and railings 30 connecting these posts, guard the open side of the stairway. While only two adjoining stair sections have been shown, it will be understood that any number of successive sections may be utilized, and that the length and width of these sections may be varied as desired.

From the foregoing description, it will be apparent that the individual treads 12, 13, 14, 15 may be readily constructed of concrete or the like and subsequently assembled to produce stairways of any desired length, either open, or partially enclosed, or completely enclosed. The treads are all of standard height from one tread surface to the next, and the tread surfaces are all of the same breadth measured in the direction of the stairway, thereby maintaining constant inclination of the stringer rods 22. After the treads have been assembled, the walls 17 and floors may be cast to maintain the assemblage in final position. The tongue and groove connections between the successive treads, not only produce a firm interlock, but also provide fire and water-proof joints. The treads 12 may be formed in the same or similar molds, and are interchangeable with each other. The lower faces of the treads 12 are parallel to the stringer holes, thus presenting a neat appearance at the bottom of the assembled treads. The structure can obviously be manufactured and assembled at relatively low cost, and the assemblage is strong, durable and of highly finished appearance.

It should be understood that it is not desired to limit the invention to the exact details of construction herein shown and described, for various modifications within the scope of the claims may occur to persons skilled in the art.

It is claimed and desired to secure by Letters Patent:

1. In a stair structure, a series of treads having abutting faces and complementary

5   tongues and grooves adjoining said faces, and elongated connecting elements extending through said treads transversely of said tongues and grooves.

10   5. 2. In a stair structure, a series of individual treads formed of moldable material and each having a tongue at one edge and a groove of similar contour at the opposite edge portion thereof, and means extending directly through all of said treads for connecting the successive treads to maintain the adjoining tongues and grooves thereof in interlocked relationship.

15   3. In a stair structure, a series of identical treads each having a tongue interlocking with a groove of an adjacent tread, a special tread interlocking with one of said first-mentioned treads, and means extending directly through all of said treads for connecting said treads to maintain them in interlocked relationship.

20   4. In a stair structure, a series of identical treads each having a tongue interlocking with a groove of an adjacent tread, special upper and lower end treads interlocking respectively with the upper and lower of said identical treads, and means extending directly through all of said treads for connecting the same to maintain them in interlocked relationship.

25   5. In a stair structure, a series of identical treads each having a tongue interlocking with a groove of an adjacent tread, special upper and lower end treads interlocking respectively with the upper and lower of said identical treads, and elongated elements extending through said identical treads and into said special treads.

30   6. In a stair structure, two adjacent series of identical treads, directly interlockable with each other, a single intermediate tread of approximately double the length of one of said identical treads coacting with the upper and lower end treads of said series, and rod members connecting said intermediate tread with said upper and lower end treads.

35   7. In a stair structure, two adjacent series of identical treads, a single intermediate tread of approximately double the length of one of said identical treads interlocking with the upper and lower end treads of said series, and stringer rods secured to said intermediate tread and extending through the treads of said series.

40   8. In a stair structure, a plurality of treads each formed for direct interlocking engagement with the adjoining treads, and a rod member connecting all of said treads and extending therethrough in a direction parallel to the assembled stairway.

45   9. In a stair structure, a plurality of one-piece treads each provided with a tongue at one edge and a groove at its opposite edge formed for direct interlocking engagement

50   with the adjoining treads, and a rod member passing directly through all of said treads in the same direction.

55   10. In a stair structure, a plurality of treads having alined inclined holes extending transversely therethrough, each of said treads having its opposite ends formed for direct interlocking engagement with the adjoining treads, and a straight rod member extending through said alined holes.

60   11. In a stair structure, a plurality of edgewise cooperable treads having alined straight holes extending entirely therethrough, and a straight rod member extending through said holes and disposed parallel to the direction of extent of the assembled stairway.

65   12. In a stair structure, a plurality of edgewise interlockable treads having alined straight inclined holes extending entirely therethrough from the lowermost to the upper portion thereof, and a straight rod member extending through said holes and disposed parallel to the direction of extent of the assembled stairway.

70   In testimony whereof, I affix my signature.
JULIUS FRICK.
